UNITED STATES PATENT OFFICE

ALBERT J. D. OHM, OF OAK PARK, ILLINOIS, ASSIGNOR TO BEARDSLEE CHANDELIER MANUFACTURING COMPANY, OF CHICAGO, ILLINOIS, A CORPORATION OF DELAWARE

DESIGN FOR A LIGHTING FIXTURE

Application filed July 31, 1930. Serial No. 36,526. Term of patent 3½ years.

To all whom it may concern:

Be it known that I, ALBERT J. D. OHM, a citizen of the United States, residing at Oak Park, in the county of Cook and State of Illinois, have invented a new, original, and ornamental Design for Lighting Fixtures, of which the following is a specification, reference being had to the accompanying drawing, which forms a part hereof.

My invention as illustrated relates to a suspended type of lighting fixture.

In the drawing:

The figure is a perspective view of a lighting fixture showing my new design; the opposite side of the fixture being identical in appearance with the side shown in the drawing.

I claim:

The ornamental design for a lighting fixture as shown and described.

ALBERT J. D. OHM.
